UNITED STATES PATENT AND TRADEMARK OFFICE
CERTIFICATE OF CORRECTION

PATENT NO. : Des. 281,323
DATED : November 12, 1985
INVENTOR(S) : Overcash, et al.

It is certified that error appears in the above-identified patent and that said Letters Patent is hereby corrected as shown below:

On the front page of the Patent, Column 1, line 22, after Driscoll, delete "538/184" and insert --338/184-- in its place. In Column 2, line 3, delete "Halley" and insert --Holley-- in its place.
